DUST COLLECTOR HOOD CONSTRUCTION

Robert Jaron, Pawtucket, R. I.

Application January 30, 1953, Serial No. 334,117

3 Claims. (Cl. 51—273)

1

The present invention relates to the suction collection of polishing, buffing and grinding dust, and has particular reference to a novel construction for a dust collector hood for the polishing of small articles such as earrings and the like.

Dust collector hoods for the polishing of small articles are mounted on a bench or table to extend over the polishing wheel, and have an opening in the base of the hood communicating with a suction pipe, whereby the dust is continually withdrawn from the hood as the polishing proceeds. When the articles to be polished are small, such as earrings and the like, there is danger of loss, as the suction opening is normally located at the rear of the hood and any article which becomes loose falls directly into the opening.

The principal object of the invention is to provide a simple and inexpensive hood construction which exits dust from the polishing operation through the suction opening while effectively preventing loss of small articles.

Another object of the invention is to provide a dust receiving compartment in a dust collector hood which is positioned to directly receive polishing dust while being out of the line of fall of an object being polished.

A further object of the invention is to provide a dust receiving compartment in a dust collector hood with a removable wire screen, which may be readily removed and cleaned when necessary.

With the above and other objects and advantageous features in view, the invention consists of a novel arrangement of parts more fully disclosed in the detailed description following, in conjunction with the accompanying drawings, and more specifically defined in the claims appended thereto.

In the drawings,

Fig. 1 is a perspective view of a preferred construction for a dust collector hood embodying the invention, the hood being shown mounted on a work table and partially enclosing a polishing wheel;

Fig. 2 is a vertical section on the line 2—2 of Fig. 1; and

Fig. 3 is a perspective view of the removable wire screen.

Referring to the drawings, the novel dust collector hood 10 includes a base 11 of trapezoid form, vertical sides 12, 13 and a shaped back plate 14, the parts being preferably of sheet metal. The sides have their lower edges 15, 16 seated on the tapering side edges of the base, and their rear edges 17, 18 arcuately shaped as illus-

2

trated; the back plate has its bottom edge 19 seated on the rear edge of the base and its rear edges 20, 21 conforming to and seated on the side rear edges, the meeting edges being received in angle strips 22 and preferably soldered thereto. The front edges 23, 24 of the sides are recessed arcuately to receive a transverse rotatable shaft 25 on which a polishing wheel 26 is keyed, to substantially house the wheel in the hood.

10 The back plate has its upper portion 27 bent to extend over and cover the wheel, and preferably to project outwardly beyond the sides 12, 13, and the side 24 is recessed to a greater extent than the side 23 to accommodate a right-handed operator who can thus readily insert an article to be polished into the hood to engage the lower edge of the wheel.

15 A transverse partition 28 is provided, having a lower upright portion 29 which extends vertically from the base in slightly spaced tangential relation to the rear portion of the wheel, and then upwardly and rearwardly as a top portion 30 to the back plate. The sides and the back edge of the partition are respectively secured to the inner surfaces of the hood sides and the back plate, whereby a compartment 31 is formed at the lower rear end of the hood, having the partition 28 as its front wall. The upright partition portion 29 has an opening 32 at its upper end which is spaced above the base and is preferably centrally aligned with the lower edge of the wheel to directly receive the polishing dust therefrom.

20 A removable wire screen covers the opening 32, the screen being designated 33 and being slidably seated in a trough 34 secured to the partition portion 29 just below the opening 32; the side 13 is provided with a vertical slot 35 through which the screen may be inserted and removed, a manually graspable ring or the like 36 being provided for this purpose. The sides 37, 38 of the screen are tapered to conform to the angularity of the sides 12, 13 and the wire mesh 40 of the screen is of a gauge to correspond to the size of the articles being polished.

25 The base 11 has a suction opening 41 within the compartment 31, preferably in the base portion forming the bottom of the compartment. The opening 41 has a depending annular flange 42, whereby the hood may be set on a work bench or table which has a suction pipe 43 secured thereto, with the flange 42 removably seated in the suction pipe.

30 The novel dust collector hood is thus readily mounted on a work bench or table, to receive 55 polishing, buffing or grinding dust from the

wheel through the wire screen and to transfer the dust through the compartment into the suction pipe, the dust receiving opening being in direct line with the lower edge of the wheel and the suction pipe opening being closed to direct entry of articles being polished by the lower part of the front partition. Small articles such as earrings will not, therefore, be drawn into the suction pipe and instead will fall on the base in front of the compartment, where they may be 10 readily reached and removed.

Although I have described a specific constructional embodiment of the invention, it is clear that changes in the size, shape and arrangement of the parts may be made to comply with different polishing, buffing, or grinding operations, without departing from the spirit or the scope of the invention as defined in the appended claims.

I claim:

1. A dust collector hood having a base, sides, and a back plate, said sides having recessed front edges for receiving the shaft of a polishing wheel, a compartment at the lower rear end of the hood having a front transverse partition extending 25 between the sides and upwardly from the base and to the back plate, said compartment having a suction opening in the lower portion thereof and said partition having an opening at a height for receiving polishing dust from the lower portion of the polishing wheel, and a screen extending across said partition opening.

2. A dust collector hood having a base, sides, and a back plate, said sides having recessed front edges for receiving the shaft of a polishing wheel, 30 a compartment at the lower rear end of the hood

having a front transverse partition extending between the sides and upwardly from the base and to the back plate, said compartment having a suction opening in the lower portion thereof and said partition having an opening at a height for receiving polishing dust from the lower portion of the polishing wheel, and a screen slidably mounted on said partition and extending across said partition opening, one side of the hood having a slot aligned with the screen for insertion and removal thereof.

15 3. A dust collector hood having a base, sides, and a back plate, said sides having recessed front edges for receiving the shaft of a polishing wheel, a compartment at the lower end of the hood having a front transverse partition extending between the sides and upwardly from the base and to the back plate, said compartment having a suction opening in the lower portion thereof having a depending flange and said partition having an opening at a height for receiving polishing dust from the lower portion of the polishing wheel, and a removable screen extending across said partition opening.

ROBERT JARON.
